UNITED STATES PATENT OFFICE.

RUDOLPH KLEMM AND MAX RORARIUS, OF UNION HILL, NEW JERSEY.

METHOD OF EMBROIDERING.

No. 924,795.

Specification of Letters Patent.

Patented June 15, 1909.

Application filed March 18, 1909. Serial No. 484,171.

To all whom it may concern:

Be it known that we, RUDOLPH KLEMM and MAX RORARIUS, both subjects of the German Emperor, residing at Union Hill, in the county of Hudson and State of New Jersey, have invented certain new and useful Improvements in Methods of Embroidering, of which the following is a specification.

The present invention relates to a novel 10 method of embroidering and particularly to a method of producing relief embroidery designs by hand or shuttle looms on any kind of material, as muslin, linen, net, etc.

The new method consists in that the design 15 is first embroidered on the goods in ordinary manner, then a lining is sewed to the back of the goods along the contour of and across the design; then the design at one end is severed from the goods, whereby a pocket 20 or cavity is formed between the goods and lining, which pocket is stuffed with cotton or other material to produce the relief effect.

To make the invention more clear the same 25 is illustrated in the accompanying drawing, in which similar reference letters denote corresponding parts and in which—

Figure 1 shows a front view of a piece of 30 embroidered goods; Figs. 2, 3 and 5 are cross sections illustrating the different phases of the embroidering method, and Fig. 4 is a rear view of the embroidered goods.

a denotes the goods upon which in ordinary manner the designs *b* are embroidered. In the present example the designs are twigs, 35 the blossoms *c* of which are to appear in relief, from the point *d* to the cross border *e*. To produce this effect a lining *f* of any suitable material, preferably of like material as the goods, is sewed to the back of the latter, 40 the stitches *g* being made through the embroidered contour of the design and in the present example also through the border *e*. When the lining is attached the design is severed from the goods along the border *e*,

the lining, which is sewed to the goods 45 around the part of the contour below the border *e* and crosswise to the goods above the border forming the back part of the pocket *h* thus produced. The unnecessary parts of the lining outside of the stitches 50 can be cut away and the cavity or pocket *h* is stuffed with suitable material, as cotton or the like, whereby the outer part *i* of the pocket is projected and the relief effect obtained. 55

Generally the lining will be a long continuous piece, as the goods upon which the designs are embroidered and the unnecessary parts of the lining will be cut away when the work is completed. When the lining is 60 of the same material as the goods the insertion or attachment of the lining will be almost unnoticeable.

When the entire blossom or other design is to appear in relief, instead of, as in the 65 present example only up to the border *e*, it is understood that the stitches in sewing on the lining to the back of the goods, will have to be made through the embroidered contour of the design all around and the severance 70 made on any side or end of the design.

What we claim and desire to secure by Letters Patent is:—

A method of producing relief embroidery 75 designs, consisting in embroidering the design in ordinary manner upon the goods, sewing to the back of the latter through the contour of the design a lining, severing the design from the goods at any side and stuffing the pocket or cavity thus produced. 80

In testimony whereof we affix our signatures in presence of two witnesses.

RUDOLPH KLEMM.
MAX RORARIUS.
